his Atty.

UNITED STATES PATENT OFFICE.

GUSTAF ANDERSON, OF LYNN, MASSACHUSETTS.

DEVICE FOR CONVERTING MOTION.

1,203,563.

Specification of Letters Patent. Patented Nov. 7, 1916.

Application filed January 3, 1916. Serial No. 69,735.

To all whom it may concern:

Be it known that I, GUSTAF ANDERSON, a citizen of the United States, and resident of Lynn, county of Essex, Commonwealth of Massachusetts, have invented an Improvement in Devices for Converting Motion, of which the following description, in connection with the accompanying drawings, is a specification, like characters on the drawings representing like parts in each of the several views.

This invention relates to a device for converting reciprocating motion into the rotary motion or vice versa, and while having other and more general uses is well adapted for converting the reciprocating movement of a prime motor such as an internal combustion engine or steam engine into the rotary shaft movement for the transmission of the power thereof as required.

A prime object of the invention is to provide a device of this character wherein the amount of power lost by friction and inertia of the parts is reduced to a minimum and wherein the transmission of power is most effectively and evenly imparted to the driven shaft, resulting in largely increased efficiency over existing types of transmission for converting motion, known to me.

To this end the invention consists in providing a special form of transmitting member which may be a cam, on a rotary shaft, such cam having raised portions or lobes alternating with inset or recessed portions, and for cooperation therewith a series of heads connected together by links and engaged with the reciprocating members, each of said heads bearing a cam engaging portion preferably equipped with a roller.

The invention will be better understood from the following detailed description taken in connection with the accompanying drawings and will be thereafter pointed out in the appended claims.

Referring to the drawings: Figure 1 shows in elevation a device constructed in accordance with my invention, the inclosing housing being shown in section, and the series of engine cylinders being broken away; and Fig. 2 is an edge view of the operating mechanism removed and with the piston rods of the engine broken away.

The invention is herein shown as embodied in a four cylinder engine though it is to be understood that this is merely illustrative and that a greater or less number of

cylinders may be employed as desired, or

the invention used for other purposes than

engine transmission. The four cylinders of

the engine indicated at 1, 2, 3, 4 are mounted

60

in quadrantal radial relation on a suitable

housing frame 5, which may also be

equipped with bearings (not shown) for a

shaft 6 to be driven by the engine. On this

shaft is fixed a special form of peripheral

65

cam having oppositely extending lobes 7, 8,

with intermediate inset or recessed portions

9, 10. The four piston rods extending in

from the respective cylinders are indicated

70

at 11, 12, 13, 14, respectively. Each of these

rods has at its inner end a yoke head 15 in

which is journaled a pin 16. These several

pins are engaged by sleeve bearing ends 17

on a series of link bars 18, 19, 20, 21 which

75

thus constitute a form of parallel motion

mechanism whereby as either or both of a

pair of the opposite heads 15 are pressed in-

ward, the other opposite pair will be forced

outward, and as any one or both of an oppo-

site pair of said heads are moved outward,

80

the other pair are likewise drawn inward.

The heads 15 are also equipped with cam en-

gaging members, these preferably consisting

in rolls 22 journaled at the lower ends of

85

the pins 16. It will be understood that the

cam portions 7, 8, 9, 10 are so proportioned

that the rolls 22 thus operated by the heads

15 connected as described, will follow the

contour of the cam. Thus as power impulse

is imparted to either or both of the opposite

90

rods, *e. g.*, the rods 11, 13, the cam and hence

the shaft 6 will be caused to rotate from the

position shown, the other pair of rods 12, 14

95

being at the same time gradually moved out

of the inset or socket portions 9, 10 of the

95

cam until finally the rolls connected with

these latter rods are engaged with the tops

of the lobes 7, 8, whereupon the rods 12, 14

100

commence to move inward, thus continuing

the forward movement of the driven cam

and shaft. Since all four of the heads 15

are connected together by the parallel link

motion described, it will be understood that

the mechanism is operated whether the

power impulse be only operating to pull on

the several rods 11, 12, 13, 14, or to push only

105

on said rods, or to both pull and push, *i. e.*

exert power in both directions of reciproca-

tion. Likewise it will be understood that

the device is equally operative and useful to

110

transmit power in the reverse direction, *i. e.*,

with the shaft 6 as the source of power and

a power delivery being to one or more of the radial rods 11, 12, 13, 14.

I am aware that the invention may be embodied in other specific forms without departing from the essential attributes thereof, and I therefore desire the present embodiment to be considered as illustrative and not restrictive, reference being had to the appended claims, rather than to the foregoing 10 description to indicate the scope of the invention.

Having described my invention, what I claim as new and desire to secure by Letters Patent is:

- 15 1. A device for converting motion consisting in a rotary shaft having a cam fixed thereon with a pair of oppositely disposed raised lobes alternating with oppositely disposed inset portions, a plurality of reciprocating members extending substantially at right angles to each other and each having an element engageable with said cam, and a pivoted link bar connection between the inner ends of said reciprocating members for the purpose stated.
- 20 2. A device for converting motion, comprising a shaft having a cam fixed thereon

formed with oppositely disposed raised lobes alternating with oppositely disposed inset portions, two pairs of reciprocating members mounted to coöperate with said cam, the members of each pair being oppositely disposed and the two pairs being at right angles to each other, and a parallel link bar connection between the inner ends of said members, the inner ends of said members having each a roller continuously engageable with said cam for the purpose stated.

3. A device for converting motion, comprising a shaft having fixed thereon a cam 40 formed with oppositely disposed lobes and with inset portions between said lobes, two pairs of piston rods mounted to coöperate with said cam, the rods of each pair being opposite each other and the two pairs at 45 right angles to each other, parallel link bar connections pivotally connecting the inner ends of said reciprocating members, each of said reciprocating members having a head equipped with a depending roll continuously 50 engageable with the periphery of said cam.

In testimony whereof, I have signed my name to this specification.

GUSTAF ANDERSON
